(57) **CLAIM**

The ornamental design for a fogger assembly housing, as
shown and described.

DESCRIPTION

The fogger assembly housing is used to house the components
of a fogger assembly. A nozzle may be mounted to the
circular fitting on the top of the housing.

FIG. 1 is a front elevation, right side elevation, top plan
isometric view of a fogger assembly housing showing our
new design; and,

FIG. 2 is a rear elevation, left side elevation, top plan
isometric view thereof.
